UNITED STATES PATENT OFFICE.

JAMES C. BOYD, OF PITCAIRN, PENNSYLVANIA.

SIGN.

Application filed September 14, 1922. Serial No. 588,233.

To all whom it may concern:

Be it known that I, JAMES C. BOYD, a citizen of the United States, residing at Pitcairn, in the county of Allegheny and State 5 of Pennsylvania, have invented certain new and useful Improvements in Signs, of which the following is a specification.

This invention relates to signs, more particularly to license or number plates for motor vehicles somewhat similar to my Patent 10 No. 1,329,454, but it is to be understood however that the invention can be employed for any purposes wherein it is found to be applicable.

15 The objects of the invention are to provide a license plate, in a manner as hereinafter set forth, with the numbers or digits so set up as to be quickly read at a distance and of a form which will readily attract one's attention, and furthermore to provide the numbers or digits of the plate one of a different color from an adjacent number of digit so they will be very conspicuous and quickly seen.

20 25 Further objects of the invention are to provide a license plate of the type stated which embodies means and a light element making the plate as discernible at night as in daytime, which provides a substitute for the ordinary tail light, which is constructed 30 from individual digit or number units permitting of the removal or replacement of the single numbers or digits from the plate without disturbing the position of the other digits or numbers, which is ornamental, durable 35 and efficient in its use, conspicuous and inexpensive.

With the foregoing and other objects in view the invention consists of the novel construction, combination and arrangement of 40 parts as hereinafter set forth and illustrated in the accompanying drawings wherein is shown an embodiment of the invention, but it is to be understood that changes, variations, and modifications can be resorted to 45 which come within the scope of the claim hereunto appended.

In the drawings wherein like numerals of 50 reference designate corresponding parts:—

Figure 1 is a front elevation of a motor license plate in accordance with the invention.

Figure 2 is a front elevation of an individual unit formed with a single digit.

55 Figure 3 is a transverse sectional view of the device.

Figure 4 is a front view of the lamp casing with the digit units removed therefrom.

Referring to Figure 1 of the drawings the license plate 1 comprises a plurality of small 60 sheet metal members 2 and may be of any suitable contour, preferably rectangular as shown.

Each of the members 2 consists of a front sheet 3 and a rear sheet 4, secured together 65 by a bolt 5 with the rear sheet 4 positioned slightly in advance of the front sheet 3 for the purpose of providing an interengaging overlapping connection with adjacent sheets.

Each of the members 2 is provided with 70 a designation on the front sheet 3 which in the plate illustrated, consists of a number or digit. As shown in Figure 1, the digits five, one, seven, naught and six are used in the composite plate 1 and are indicated at 6, 75 7, 8, 9 and 10 respectively. The plate is illustrated by way of example with five digits reading fifty one thousand seven hundred and six, but it is obvious that the number of digits can be increased or diminished as desired. The end member is provided with the usual designations, and representing, respectively, the State and year in which the license is issued.

Each of the digits used in the assembly of 80 a license plate is preferably represented in a different color relatively to each other, or at least with respect to an adjacent digit, so that they will more readily attract attention as well as providing a conspicuous number.

As shown in the plate 1, the digit 6 is yellow, the digit 7 green, the digit 8 blue, the digit 9 red, and the digit 10 purple. Under 90 these conditions the digits are of a different color on each of the members.

The digit shown on each of the members 2, besides being painted on the latter in a color desired, is also formed in the same color by arranging a plurality of small colored 100 lenses to form the digit which is painted on the said member 2.

The lenses are indicated at 11 and have a flat rear surface and a convex front face. The lenses 11 are clamped between the two 105 sheets 3 and 4 which are formed with registering apertures provided for said lenses 11. The apertures in the sheets 3 and 4 are of less diameter than the diameter of the lenses so the latter cannot pass therethrough. The 110 convex side of the lens 11 projects slightly through the aperture in the front sheet 3.

The members 2 are securely positioned to form the plate 1 by means of a bolt 12 which extends through each end of each of the members 2 and engages the apertured flange 13 of the lamp casing 14.

A lamp 15 is mounted in the rear central portion of the casing 14 and is adapted for displaying the digits outlined by the lenses 11 on respective members 2. The interior wall of the casing 14 is utilized as a reflector for the lamp 15 in projecting the light through the lenses 11. The rear wall of the casing 14 is formed with apertures 17 for attaching the casing to the motor vehicle. The casing 14 may be of any desired contour to best meet conditions found in practice.

It will be noted that in the daylight my improved license plate will be used without the use of the lamp 15 and the painted digits may be readily read from a distance. At night with the aid of the lamp 15 the same

colored digits will be shown through the lenses 11 and will be more prominent and conspicuous than the painted digits for daylight use, and will also serve as a substitute 25 for the usual tail light for the motor vehicle.

What I claim is:—

A device for the purpose set forth comprising a lamp casing provided with a flange, a lamp mounted in said casing, a plurality of plates detachably secured to said flange, each of said plates consisting of a pair of apertured metal sheets secured together one in advance of the other, said apertures in each plate arranged to designate a digit, a lens clamped in each of said apertures, the lenses of one of said plates being of a color different relatively to the color of the lenses mounted in an adjacent plate substantially as described.

In testimony whereof I affix my signature.

JAMES C. BOYD.
